KEYCASE

Adolphe Margottat, Yzeure, France, assignor to Societe Anonyme Francaise de Maroquinerie Sans Couture "Le Tanneur" et Tanneries du Bugey, Belley (Ain), France, a company

Application May 20, 1954, Serial No. 431,203

Claims priority, application France June 15, 1953

3 Claims. (Cl. 150—40)

The present invention relates to keycases and more particularly to keycases of the type comprising a foldable case internally fitted with an apertured plate adapted to receive removable key-carrying rings.

One object of the invention is to provide a keycase of the type referred to in which the key-carrying rings may be hooked in or released from the apertured plate in a very simple manner and in which said rings may be opened or closed in a new and improved manner.

Another object of the invention is to provide a keycase of the type referred to wherein the apertured plate which constitutes the support for the key-carrying rings is arranged in such a manner as to cooperate with the case for ensuring the locking of said rings or for allowing their release in accordance with the position of the apertured plate with respect to the case proper.

A further object of the invention is to provide locking means for locking said apertured plate on the case.

Still a further object of the invention is to provide a key-carrying ring having a spherical head and which is easy to manufacture though readily set into opened or closed position.

According to the main feature of the invention, the apertured plate which constitutes the support for the key-carrying rings is hingedly mounted inside the case proper so that it may be swung away from or toward the case.

According to another feature of the invention, each key-carrying ring is formed into a loop with two adjacent rectilinear legs of unequal lengths, the longer one of which is terminated into a spherical head adapted to be engaged into the apertures of the supporting plate while a sliding sleeve threaded over said leg is adapted to embrace or to release the other leg for respectively closing or opening the ring.

Other and further objects and advantages of the invention will be apparent to those skilled in the art, from a consideration of the following description of one specific embodiment of the invention, shown by way of example, in the accompanying drawings, in which:

Fig. 1 is an elevational front view of a keycase according to the invention, as seen in open position,

Fig. 2 is a top view corresponding to Fig. 1,

Fig. 3 is a top view showing the apertured plate in open hinged position,

Fig. 4 is a sectional view, on a larger scale, made on line IV—IV of Fig. 1,

Fig. 5 is a sectional view, also on a larger scale, made on line V—V of Fig. 1,

Fig. 6 shows the rear face of the apertured plate,

Fig. 7 is a perspective view of the plate which supports the pivot pin for the apertured plate,

Fig. 8 shows the introduction of the spherical head of a key-carrying ring into one of the transversal slots of the supporting plate, and

Fig. 9 is a detail view showing the key-carrying ring in the open position.

Referring to these figures, it is readily seen that the keycase is constituted by a foldable envelope made of flexible material, such as leather or a plastic material for instance, said envelope having a central portion 1 and two lateral flaps 2 and 3 adapted to be folded flat one on the other by virtue of the folding crease lines 4, and secured together by press-buttons 5, 6. According to the invention the central portion 1 is overlaid by a flap 7 connected to said portion as at 7a by means of a stitching or adhesive seam forming hinge means. To the flap 7 is

2

secured a supporting plate 9 as by means of rivets 8. The supporting plate 9 has in a known manner a plurality of transverse slots 10 terminating into widened recesses on the rear face of the plate (Fig. 6). The apertured 5 supporting plate 9 has along one of the transverse sides thereof one element 12 of a hinge (Figs. 4 and 5) adapted to receive a pin 13 supported by the ears 14 of a small plate 15 secured to the keycase proper.

The plate 9 has, on its other transverse side, a circular aperture 16 provided with a slot 17 opening outwardly, said circular aperture cooperating with a locking element 18 carried by the plate 15. This locking element 18 comprises a turn button 19 with a spring and of the same width as the slot 17, in order to enable the flap 7 and the apertured plate 9 to be clamped flat against the central portion 1 of the keycase.

According to the invention, the key-carrying ring is made from a material such as piano wire for instance, suitably shaped into a lower loop portion 21 and two rectilinear legs 22 and 23 having different lengths. The leg 22 is terminated into a spherical head 24. Both legs 22 and 23 are housed within a sleeve forming a sliding ring 25 with an axial bore 26 opening into a cylindrical recess 27 of a larger diameter.

The use of the keycase above described and shown in the drawings is as follows:

When it is desired to turn open the flap 7 together with the apertured plate 9, as shown in Fig. 3, it merely suffices to register with the slot 17 in order to release the supporting plate 9 which now may be swung on the pin 13, while the flap 7 itself is able to pivot on the stitching line or seam 7a. Conversely, subsequent to the flap 7 and the plate 9 being folded flat against the central portion 1, the turn button 19 is again rotated so as to be brought into the position shown in Figs. 1 and 2; under such conditions the flap 7 and the plate 9 are securely locked against the central portion 1.

When it is desired to open the key-carrying ring 20, this ring should first be released out of the widened portions 11 of one of the lateral slots 10, as represented in Fig. 8, and the sliding ring 25 is then shifted in the direction of the arrow f (Fig. 5). This results in the possibility for the rectilinear leg 23 to be freed from the axial bore 26 while the spherical head 24 now is housed within the recess 27 (Fig. 9). After this operation has been carried out, it is now possible to thread a key into the ring 20, and then to bring back the leg 23 flat against the leg 22. The sliding ring 25 is shifted in the direction of the arrow f (Fig. 9) in order that the leg 23 be again entrapped within the axial bore 26, which results in the key-carrying ring being closed again.

From the foregoing it is readily seen that in the improved keycase according to the invention the key-carrying rings 20 may be introduced into the lateral slots 10 of the supporting plate or released therefrom very easily. This advantage results from the fact that the apertured plate 9 and the flap 7 are pivotally mounted on the pin 13, and that the supporting plate is maintained with the key-supporting rings in place by the action of the locking element 18 while the spring turn button 19 ensures the clamping of the plate 9 and the flap 7 against the keycase. Furthermore, the key-carrying rings may be easily opened or closed with a view to insert or to remove a key by virtue of the sliding ring 25 adapted to be shifted on the rectilinear legs of the key-carrying ring and to ensure a complete clamping of the latter in its closed position.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

What I claim is:

1. In a keycase of the type comprising a foldable case internally fitted with an apertured supporting plate adapted to receive removable key-carrying rings, the provision of a rigid plate secured to said case on the inner face thereof, hinge means having one element rigid with said rigid plate and another element rigid with said aper-

tured supporting plate for pivotally supporting said supporting plate, said supporting plate being rolled so as to comprise a rear face adapted to lie flat against said case and a front face, both said faces being connected together by an arched portion of said supporting plate, the apertures of said apertured supporting plate being shaped into slots extending transversely from said front face through said arched portion and terminating into enlarged recesses located on said rear face of said supporting plate, said removable key carrying rings being each in the shape of a loop with two adjacent parallel rectilinear legs of unequal lengths, the longer one of which has its end portion shaped into a ball-like head of a size between the widths of said slots and said enlarged recesses of said apertured supporting plate so as to be adapted to be introduced into said enlarged recesses and retained by the edges of said slots, a sliding sleeve being slipped over said longer leg of said key-carrying ring and adapted according to its position along said leg to embrace or to release the other shorter leg of said ring, and locking means being provided for locking said supporting plate flat against the inner face of said case.

2. In a keycase of the type comprising a foldable case internally fitted with an apertured supporting plate adapted to receive removable key-carrying rings, the provision of hinge means carried by said case for pivotally supporting said supporting plate, said supporting plate being rolled so as to comprise a rear face adapted to lie flat against said case and a front face, both said faces being connected together by an arched portion of said supporting plate, the apertures of said apertured supporting plate being shaped into slots extending transversely from said front face through said arched portion and terminating into enlarged recesses located on said rear face of said supporting plate, said removable key carrying rings being each in the shape of a loop with two adjacent parallel rectilinear legs of unequal lengths, the longer one of which has its end portion shaped into a ball-like head of a size between the widths of said slots and said enlarged recesses of said apertured supporting plate so as to be introduced into said enlarged recesses and retained by the edges of said slots, a sliding sleeve being slipped over said longer leg of said key-carrying ring and adapted according to its position along said leg

5 to embrace or to release the other shorter leg of said ring, and locking means for locking said apertured supporting plate flat against the inner face of said case comprising a turn button mounted on said case and a slot cut out in said supporting plate and adapted to register with said turn button when applied against the inner face of said case.

3. In a keycase of the type comprising a foldable case internally fitted with an apertured supporting plate 10 adapted to receive removable key-carrying rings, the provision of hinge means carried by said case for pivotally supporting said supporting plate, said supporting plate being rolled so as to comprise a rear face adapted to lie flat against said case and a front face, both said faces being connected together by an arched portion of said 15 supporting plate, the apertures of said apertured supporting plate being shaped into slots extending transversely from said front face through said arched portion and terminating into enlarged recesses located on said rear 20 face of said supporting plate, said removable key-carrying rings being each in the shape of a loop with two adjacent parallel rectilinear legs of unequal lengths, the longer one of which has its end portion shaped into a ball-like head of a size between the widths of said slots and said 25 enlarged recesses, of said apertured supporting plate so as to be adapted to be introduced into said enlarged recesses and retained by the edges of said slots, a sliding sleeve having an axial bore of a diameter suitable for embracing said both legs of said key-carrying ring, said axial bore opening into a cylindrical counterbore coaxial therewith and having a diameter larger than that of said 30 spherical head of said ring, said counterbore being adapted to receive said spherical head when it is desired to open said ring, and locking means being provided for locking said supporting plate flat against the inner face of said 35 case.
